UNITED STATES PATENT OFFICE.

THOMAS BARBER, OF FLATBUSH, NEW YORK.

LINING FOR CYLINDERS.

SPECIFICATION forming part of Letters Patent No. 307,899, dated November 11, 1884.

Application filed June 5, 1884. (No model.)

To all whom it may concern:

Be it known that I, THOMAS BARBER, a citizen of the United States, residing at Flat-
5 bush, in the county of Kings and State of New
York, have invented new and useful Improve-
ments in Lining for Cylinders, of which the
following is a specification.

This invention relates to means for securing
10 a lining in the interior of a cylinder, said
means being pointed out in the following
specification and claims and illustrated in the
accompanying drawings, in which—

Figure 1 represents a transverse section of a
15 cylinder lined according to my invention.
Fig. 2 is a longitudinal section of the same.
Fig. 3 is a detached perspective view of one of
the bevel-headed screw-bolts on a larger scale
than the previous figures; and Fig. 4, a broken
20 sectional view on a reduced scale, showing a
modification of the invention.

Similar letters indicate corresponding parts.
In the drawings, the letter A designates a
25 cylinder which is provided with a lining, B.
The lining is made in the form of a tube which
fits the bore of the cylinder, and which is pro-
vided with a slot, a, extending throughout its
entire length. The edges of this slot are be-
30 velled, and in the cylinder is a series of holes to
receive the screw-bolts C. The heads b of
these screw-bolts have beveled sides (see Figs.
1 and 3) which engage with the beveled edges
of the slot a, so that when the nuts c of the
screw-bolts C are drawn up tight the slot a is

spread, and thereby the lining B is firmly se-
cured in the cylinder. The heads b must be 35
so constructed that the same do not project
beyond the inner surface of the lining when
the nuts are drawn up tight.

In Fig. 4 I have shown the slot between the
bolt-heads filled with an expanding strip, a', 40
of wood or other suitable material, the strip
being of such thickness as not to rise above
the level of the lining. As shown, this ex-
panding strip is provided with countersunk
45 holes to receive the heads of the bolts, which
thus serve to retain the strip in place; but in-
stead of such construction the expanding strip
may be formed by connecting the bolts to a
head common to all of them, or separate fill-
50 ing-pieces used.

What I claim as new, and desire to secure
by Letters Patent, is—

The combination, with a cylinder, of a lin-
ing provided with a slot which has V-shaped
55 edges, and of screw-bolts passing through
holes in the cylinder, and having heads with
V-shaped sides to engage with the V-shaped
edges of the slot, substantially as and for the
purpose described.

In testimony whereof I have hereunto set 60
my hand and seal in the presence of two sub-
scribing witnesses.

THOMAS BARBER. [L. S.]
